UNITED STATES PATENT OFFICE.

FRED I. TONE, OF INDIANAPOLIS, INDIANA.

CAM-SHAFT-OPERATING MEANS FOR INTERNAL-COMBUSTION ENGINES.

1,300,518.

Specification of Letters Patent. Patented Apr. 15, 1919.

Application filed September 16, 1916. Serial No. 120,498.

To all whom it may concern:

Be it known that I, FRED I. TONE, a citizen of the United States, residing at Indianapolis, Marion county, and State of Indiana, have invented and discovered certain new and useful Improvements in Cam-Shaft-Operating Means for Internal-Combustion Engines, of which the following is a specification.

10 My invention relates to a cam shaft operating mechanism for internal combustion engines and its object is to provide means for operating the valve operating cam shaft from the main shaft which shall dispense with a continuous train of gears or a chain for such purpose which is particularly adaptable for coöperation with valves mounted in the cylinder heads and also to engines having two or more sets of cylinders 15 arranged at an angle to one another and which shall enable the employment of a single connecting and driving member common to the cam shafts of all the sets of cylinders and to provide adjusting means 20 whereby a proper centering and interfitting of the parts of said mechanism may be obtained when the same are assembled notwithstanding inequalities in the form of the various parts due to construction or 25 wear.

With these objects and others in view my invention is embodied in preferable form in the construction and arrangement herein-after described and illustrated in the accom-

30 panying drawings.

In these drawings, Figure 1 is an end view partly in vertical section of an engine embodying my improvements, Fig. 2, a horizontal section on line 2—2 of Fig. 1; Fig. 3, an enlarged detail end view partly in section of the coupling at the upper end of the operating frame and Fig. 4 a section on line 4—4 of Fig. 3.

Referring to the drawings, the invention 45 is shown as applied to a nine-cylinder engine in which 1 are the cylinders of a central row, the units of which are arranged vertically and 2 and 3 respectively are the cylinders of two left and right hand side 50 rows of cylinders, disposed at a V-angle of 80° to one another. However a greater or less number of cylinders may be employed in connection with a construction embodying the main features of my invention, al- 55 though the latter as a whole particularly co-

operates with the arrangement shown. The valves for the cylinders are arranged in vertical heads 5 above the cylinders, those heads for the two side sets extending at an angle to the axes of their respective cylinders and parallel to the vertical heads of the central set whereby ready accessibility to all the valves is afforded and a compact arrangement of heads and cylinders obtained. 6 designates the pistons, 7 the connecting rods, 8 a crank pin and 9 the main driving shaft.

On the shaft 9 at the front end thereof is a gear wheel 10 which is adapted to mesh with and drive gears 11 and 12 mounted on 70 stub shafts 13 and 14, one on each side of said main shaft. Each of these gear wheels 11 and 12 carries a crank 15. On these cranks is mounted the cam shaft-driving and connecting member consisting of an integral 75 sheet metal frame 16, having a central vertical arm 17 and two side arms 18 and 19 corresponding respectively to the cam shafts of the central and side sets of cylinders.

At the junctions of the arm 17 with each 80 of the arms 18 and 19, the member is provided with an enlargement 20 forming a bearing which surrounds the crank 15. A ball bearing 21 is interposed between the crank and enlarged portion of said member. 85

The arm 17 is straight while the arms 18 and 19 are bent angularly in order to follow the axes of their respective cylinders and heads.

The upper end of each arm is provided 90 with an eccentric ring 22 adapted to surround an eccentric collar 23 carried on a crank pin 24 of a crank consisting of a sleeve or boss 25 and disk 26 which disk is bolted to the cam shaft 27. The crank pin 24 is 95 connected to the crank sleeve 25 by means of a bolt 28 having at one end a hexagon head, and having its opposite end threaded, and having such threaded end adapted to engage an interiorly threaded wedge-shaped nut 29 in a recess in one end of the crank pin 24, which end is split so that when the bolt is tightened by turning its hexagon head the wedge member 29 will be drawn in against the crank pin and expand the latter against the sleeve 25 so as to bind said parts together.

An annular ball bearing 30 is interposed between the collar 23 and the crank pin 24. The hexagon head of the bolt 28 bears 110

against the annular bearing, forcing the same against the sleeve 25. The openings in the annular bearing and the sleeve 25 are adapted to register when the head members 5 and other parts of the motor fit together properly. Owing to slight inequalities in the parts or to wear in the gasket at the base of the heads, the parts may not fit exactly thus changing the distance between 10 the centers of the cam shaft and stub shaft and between the centers of the driving and driven cranks which would prevent the correct engagement of the arms of the driving member 16 with the cam shafts unless provision were made for taking care of this 15 lack of registry. This objection is overcome by circularly shifting the eccentrics 22 and 23 relatively to thereby so adjust the center of the annular bearing that the distances between 20 the centers of the annular bearing 30 and bearing 20 is the same as that between the centers of the cam shaft and the stub shaft 13. The one-piece three-armed frame 16 enables this adjustment to be effected in an engine of the type shown. Whenever 25 the apertures in the sleeve and annular bearing are in registry, the parts are in correct position and when such registry is effected the bolt 28 is inserted and the sleeve and bearing drawn tightly together by tightening 30 the head on the end of the bolt.

In the operation of the device the connecting member 16 will be rotated by the cranks 15 and will thus operate the cam 35 shafts 27 which carry the cams for operating the valve mechanism.

Having thus described my invention, what I claim is:

1. In an internal combustion engine, in 40 combination with an explosion cylinder, the main shaft, a valve for said cylinder, a crank driven by the main shaft, a cam shaft for operating said valve, a crank on said cam shaft, a connecting arm between said 45 cranks and a means for eccentrically adjusting the end of said arm at its connection with the second crank to adapt the centers of said arm connection and said cranks to variations in the assembled parts of the engine.

2. In an internal combustion engine, in 55 combination with an explosion cylinder, a valve for said cylinder, a cam shaft for operating said valve, a main shaft, cranks intermediate 60 said main shaft and cam shaft, an arm connecting said cranks, and having a head adapted to eccentrically fit said cam shaft crank, said crank and head having apertures adapted to register and a pin 65 adapted to be inserted in said aperture through said parts whereby when the head of the arm and the crank are adjusted so that said aperture will register the centers and said head will be in correct relative driving position.

3. In an internal combustion engine, in combination with a series of explosion cylinders arranged in rows side by side, a main driving shaft, valves for said cylinders, a cam shaft for each row of cylinders, a crank 70 driven from the main shaft, cranks carried by said cam shafts and a rigid connecting member mounted on the crank that is driven from the main shaft, and having arms connecting respectively at their ends with the 75 cranks of said cam shafts.

4. In an internal combustion engine, in combination with a series of explosion cylinders arranged in three rows side by side, valves for said cylinders, valve operating 80 means, a main shaft, gear wheels mounted on opposite sides of said shaft, and driven therefrom, a crank carried by each gear wheel, a member for operating said valve operating means and pivotally connected to 85 each of said cranks, and having arms connected to said valve operating means.

5. In an internal combustion engine, in combination with a series of explosion cylinders arranged in three rows side by side, 90 valves for said cylinders, valves actuating means, a main shaft, and a member common to all of said valve operating means and driven from the main shaft and having two centers of rotation, one on each side 95 of said main shaft.

6. In an internal combustion engine, in combination with a series of explosion cylinders arranged in three rows side by side, valves for said cylinders, a valve operating 100 cam shaft for each row, a main shaft on a pair of gears one on each side the said main shaft and driven therefrom, cranks carried by said gears, cranks carried by said cam shafts and a rigid connecting frame common to all of said cam shafts and having three arms connected respectively to the cranks thereof, said frame being pivotally mounted on the two gear wheel cranks and adapted to be circularly driven thereby.

7. In an internal combustion engine in combination with a series of explosion cylinders arranged in three rows side by side, the cylinders of the side rows being disposed at a V-angle to the cylinders of the central row and to one another of the said cylinders having valve heads extending vertically above the cylinders in parallelism and valves mounted in said heads, means for driving said valves, a main shaft and a common connecting member between said valve operating means for the cylinders of the different rows and main shaft.

8. In an internal combustion engine in combination with a series of explosion cylinders arranged in three rows side by side, the cylinders of the central row extending vertically and the cylinders of the two side rows extending to a V-angle to those of the central row and to one another, all of said 125 130

cylinders having vertical extending heads, the heads of the cylinders of the side rows being to an angle of the axes of said cylinders, valves inclosed within said heads, cam 5 shafts for operating the valves of the respective rows, a main shaft, cranks driven by said main shaft, cranks on the cam shafts, a connecting member between the cranks driven by the main shaft and the 10 cam shaft cranks, consisting of a three armed frame, mounted to be circularly

driven by the two cranks which are driven by the main shaft.

In witness whereof, I have hereunto set my hand and seal at Indianapolis, Indiana, ¹⁵ this 13th day of September, A. D. nineteen hundred and sixteen.

FRED I. TONE. [L. S.]
